[57] CLAIM

The ornamental design for pastry, as shown and described.

DESCRIPTION

FIG. 1 is a top, front and left side perspective view of pastry embodying my new design;

FIG. 2 is a front elevational view thereof, the rear elevational view being a mirror image of the front view shown;

FIG. 3 is a top, front and left side perspective view of a second embodiment of the present invention;

FIG. 4 is a front elevational view thereof, the rear elevational view being a mirror image of the front view shown;

FIG. 5 is a top, front and left side perspective view of a third embodiment of my invention;

FIG. 6 is a front elevational view thereof, the rear elevational view being a mirror image of the front view shown;

FIG. 7 is a top, front and left side perspective view of a fourth embodiment of my invention;

FIG. 8 is a front elevational view thereof, the rear elevational view being a mirror image of the front view shown;

FIG. 9 is a top, front and left side perspective view of a fifth embodiment of my invention; and,

FIG. 10 is a front elevational view thereof, the rear elevational view being a mirror image of the front view shown.
